UNITED STATES PATENT OFFICE.

GEORGE CHURUS, OF DETROIT, MICHIGAN.

TOY BOAT.

Application filed May 26, 1925. Serial No. 33,055.

This invention relates to a miniature boat and while it is especially adapted for use in connection with Christmas displays, it will be seen that it is also capable of use for advertising and other purposes.

Briefly stated, an important object is to provide a miniature boat having novel means whereby the same may be rocked or moved back and forth to imitate a boat at sea.

A further aim of the invention is to provide a miniature boat having a number of features such as a smoke-stack to give off real smoke, a steam whistle, ladders, marine lights, a pilot house, all of which contribute to the production of a toy which may be used at Christmas time or any time desired and which is also capable of use in connection with advertising.

20 A further object of the invention is to provide a toy boat of the character specified which may be used as a source of pleasure to both the young and old.

Other objects and advantages will be apparent during the following description.

In the accompanying drawing forming a part of this application and in which like numerals are employed to designate like parts throughout the same,

30 Figure 1 is a side elevation of the improved toy, parts being in section;

Fig. 2 is a vertical transverse sectional view through the improved toy, the view being taken on line 2—2 of Fig. 1;

35 Fig. 3 is a detail sectional view taken on line 3—3 of Fig. 2.

In the drawing, wherein for the purpose of illustration is shown a preferred embodiment of the invention, the numeral 5 designates a hull which may, of course, be made of any suitable material and at this point it is desired to state that while certain materials may be preferred for some parts of the invention, other materials are suitable for 45 use in this connection and I do not wish to be restricted to the use of any particular materials. The hull 5 may be provided with a flat bottom of wood, paper, or the like, having a transversely curved upper portion 50 of wood, stout cardboard, a composition material, or the like, which may or may not be covered with a colored or figured paper.

The cradle 10 is provided with a pair of rockers 11 mounted upon a support 12.

55 Figs. 1 and 2 illustrate that the rockers 11 are mounted between a pair of spaced par-

allel guideways 14 by means of which the rockers are held against lateral movement. The support 12 is in the nature of a housing for an electric or other motor 16 which drives a wheel 18 through the medium of a belt 20, or the like. Attention is directed to Fig. 1 which shows that the wheel 18 is provided with a laterally projecting drive pin 22 which extends through a slot in one end of a lever 24. The lever 24 is fulcrumed to a bracket 26 and the outer end of the lever has connection with a link 28, the upper end of which is connected as indicated at 30 to the forward portion of the hull. It is thus seen that the operation of the electric motor 16 will result in the rocking of the hull 5 to give the hull the appearance of a boat at sea. A suitably corrugated paper or other body 34 is located on opposite sides of the hull to represent rough water.

In carrying out the invention the electric motor 16 may be provided with current from any source and a transformer 36 may be employed if necessary or expedient.

Fig. 1 illustrates that a cabin 38 is mounted on the hull and more specifically, upper and lower tiers of staterooms or cabins 38 are mounted upon the hull. An observation or pilot house 40 is mounted upon the cabin 38 and one or more figures representing Santa Claus may be located within the observation or pilot house 40.

Figs. 2 and 3 illustrate that a small boiler 50 may be located upon the hull immediately above or in operative relation to a burner 51 of any type and the steam created by the burner will travel through a whistle 52 to give a whistling sound. At one side of the boiler is located a firebox 53 in which charcoal and incense may be burned to give off real smoke through a smokestack 54. The firebox is provided with a fire door 56 by means of which the supply of fuel may be replenished. Fig. 3 shows that air inlet openings 58 are located in the side or other convenient place in the firebox.

In carrying out the invention, the front and rear masts 60 may be of wood which are preferably colored with green paper. The masts may support one or more rows of electric lights 62 and these electric lights may extend beyond the masts and to the hull as illustrated in Fig. 1. The improved boat may also be provided with marine lights 63 at any place desired and of any color or degree of brightness.

Suitable ornamental ropes of silver or the like are designated by the numeral 68 and may be connected to the masts or other parts of the boat.

5 3. Also the improved boat may be provided with Christmas birds 70 located at various places, and with ladders 64 having sides of silver rope or the like.

Having thus described the invention, what 10 is claimed is:

1. A miniaure boat comprising a hull, a cradle supporting the hull and having a pair of rockers, a housing having a flat surface supporting the rockers, a link connected 15 to the hull, a lever connected to the link and having a slotted end, and a power wheel having a drive member extended through the slotted end of said lever whereby to rock the boat.

20 2. A miniature boat comprising a hull; a cradle supporting the hull and having a pair of rockers, a housing having a flat surface

supporting the rockers, a link connected to the hull, a lever connected to the link and having a slotted end, a power wheel having 25 a drive member extended through the slotted end of said lever whereby to rock the boat, and a power unit for operating the wheel within said housing.

3. A miniature boat comprising a hull, a cradle supporting the hull and having a pair 30 of rockers, a housing having a flat surface supporting the rockers, a link connected to the hull, a lever connected to the link and having a slotted end, a power wheel having 35 a drive member extended through the slotted end of said lever whereby to rock the boat, and a power unit for operating the wheel within said housing, said supporting housing being provided with means limiting 40 the lateral movement of said rockers.

In testimony whereof I affix my signature.

GEORGE CHURUS.
